W. G. MAYER,
SUPPORTING CONNECTION FOR VEHICLE BODIES.
APPLICATION FILED APR. 7, 1919.

1,339,521.

Patented May 11, 1920.

UNITED STATES PATENT OFFICE.

WILLIAM G. MAYER, OF PITTSBURGH, PENNSYLVANIA.

SUPPORTING CONNECTION FOR VEHICLE-BODIES.

1,339,521.

Specification of Letters Patent. Patented May 11, 1920.

Original application filed November 2, 1918, Serial No. 260,869. Divided and this application filed April 7, 1919. Serial No. 287,942.

To all whom it may concern:

Be it known that I, WILLIAM G. MAYER, a citizen of the United States, and a resident of Pittsburgh, in the county of Allegheny and State of Pennsylvania, have invented a new and useful Improvement in Supporting Connections for Vehicle-Bodies; and I do hereby declare the following to be a full, clear, and exact description thereof.

10 My invention relates to vehicles, and has special reference to the body of such vehicles, this application being a division of application filed by me on November 2, 1918, Serial No. 260,869.

15 The object of my invention is to provide a cheap, simple and efficient device for connecting the sides of the body and under frame of the body together, as well as such a device which will be strong and durable 20 and will not be liable to become broken or separated when in use.

25 To these ends, my invention consists, generally stated, in the novel construction, arrangement and combination of parts, as hereinafter more specifically set forth and described and particularly pointed out in the claims.

30 To enable others skilled in the art to which my invention appertains to construct and use my improved device, I will describe the same more fully, referring to the accompanying drawings, in which:

Figure 1 shows a cross-section of an ordinary vehicle body and under frame;

35 Fig. 2 is a side elevation of the same; Figs. 3, 4, 5, 6 and 7 are detail views of the connection employed between the body and under frame, with Fig. 5 being taken on the line 5—5 Fig. 4 looking in the direction of the arrows; and

40 Figs. 8, 9, 10, 11 and 12 are detail views showing other forms of such connection, with Fig. 9 being taken on the line 9—9 Fig. 8 looking in the direction of the arrows.

Like symbols of reference herein indicate like parts in each of the figures of the drawings.

45 As illustrated in the drawings, A represents the vehicle body such as what is known as an open express body, which is provided with the usual sides 1, and under said body is the base or under frame 2. The body A has the bottom 3 formed of the central por-

tion 4 and side portions or sills 5, with such 55 sills having an inner flange portion 6 for forming a ledge on which such central portion rests, and between the bottom 3 and under frame 2 are the cross bars 7. In order to connect the sides 1 of the body A with 60 the bottom 3 of such body, the bracket supports 8 are employed, such supports being positioned adjacent to such bars 7, and with a number of the same extending along such 65 sides and between such bottom and the under frame 2. As shown in Figs. 1 to 7 inclusive, these supports 8 consist of an upright flange or angle member 9 extending vertically along the sides 1 and the horizontal lug member 10 extending under the sill 5 of the bottom 3, and such members are preferably formed of malleable iron castings or pressed metal, such as steel. These angle members 9 are outwardly flared 70 at their top portions 11 in order to conform 75 to the outwardly flared portions 12 on the sides 1 and such members are secured to such flared portions 12 and said sides by means of bolts 13 passing through side flanges 9' 80 in said members and said sides. The horizontal members 10 project slightly beyond the sides 1 of the body A at their outer ends 10' and have at such ends an angular slot 14 extending vertically through the same 85 for the reception of the lower ends of the upright members 9. A bolt 15 passes through apertures 15' in the center flange 9' on the upright members 9 and through the slot 14 and like apertures in the outer end 10' of the horizontal members 10 to hold the parts 90 in place, and bolts 16 also pass through the inner portions of the members 10 and through the sill portions 5 on the bottom 3 to connect the said members to said 95 bottom.

As shown in Figs. 8 and 9, the angular member 9 is shown for use without connection with or use of the open express body A therewith but can be used with what is known as a stake body, in which case, such member is formed straight instead of flared at its upper end, and is adapted to be removably connected with the member 10 through its lower end fitting within the slot 14 in such member 10. In order to hold the member 9 in the member 10 a clamp 17 is bolted to and around the central flange 9' on the upright member 9 in order to en-

gage with the upper face of such member 10.

In Fig. 10, the horizontal lug member 10 is shown as being formed as part of or integral with the member 9, and in Figs. 11 and 12, such members are shown with the member 9 formed of channel shape for fitting within a like shaped slot in the member 10.

10 It will thus be seen that in the use of my improved bracket supporting construction between the side panels of a vehicle body, the usual formation of these parts from wrought metal and wood will be dispensed with, and the liability of the breaking off of the end of the usual wooden portion which ordinarily projects horizontally from the sides of the body is overcome, while such metal and wooden parts are expensive and difficult to form to shape and size, so that such parts are eliminated by the connection described herein. The use of the bracket connection on the outside of the body will also eliminate the use of plates 25 and draw bolts commonly used on the inside of the body in the ordinary connections, and as shown and described such connections are preferably placed adjacent the cross bars on the under frame in order to 30 strengthen the side of the body at such point.

Various modifications and changes in the design and construction of my improved bracket supporting connection for vehicle bodies may be resorted to, without departing from the spirit of the invention or sacrificing any of its advantages.

What I claim as my invention and desire to secure by Letters Patent is:—

40 1. A vehicle body having a bottom and sides, a vertical member secured to said sides and having a flange, a horizontal socket member secured under said bottom, and se-

curing means between said flange and socket member.

2. A vehicle body having a bottom and sides, a vertical member secured to said sides and having a flange, a horizontal socket member secured under said bottom, and means for securing said flange and said socket member at their ends.

3. A vehicle body having a bottom and sides, a vertical member secured to said sides and having a flange, a horizontal socket member secured under said bottom, said socket member having a portion projecting beyond said bottom, and means for securing said flange portion to said projecting portion.

4. A vehicle body having a bottom and sides, a vertical member secured to said sides and having a flange, a horizontal socket member secured under said bottom, said socket member having a portion projecting beyond said bottom and provided with a slot within the same of the same shape as said flange portion for the reception of said flange portion, and means for securing said flange portion in said slot.

5. A vehicle body having a bottom and sides, a vertical member secured to said sides and having a flange, a horizontal socket member secured under said bottom, said socket member having a portion projecting beyond said bottom and provided with a T-shaped slot within the same of the same shape as said flange portion for the reception of said flange portion, and means for securing said flange portion in said slot.

In testimony whereof, I have hereunto set my hand.

WILLIAM G. MAYER.
